CR 014,337

EX

Design No. 14,337, dated October 2, 1883.

UNITED STATES PATENT OFFICE.

WILLIAM H. HOYT, OF STAMFORD, CONNECTICUT.

DESIGN FOR A PARLOR ORNAMENT.

SPECIFICATION forming part of Design No. 14,337, dated October 2, 1883.

Application filed August 7, 1883. Term of patent 7½ years.

To all whom it may concern:

Be it known that I, WILLIAM H. HOYT, a citizen of the United States, residing at Stamford, in the county of Fairfield and State of Connecticut, have invented and produced a new and original Design for a Parlor Ornament, of which the following is a specification, reference being had to the accompanying drawing, forming part thereof, in which the figure 10 shows in perspective my newly-designed parlor ornament.

A represents the basket or boat-shaped inclosure, made in this instance of feathers; and B represents a bird's head projecting out of the front of inclosure A. The boat-shaped inclosure A is by preference mounted upon the

base C, so that the whole will present to the eye the effect of a bird floating upon water in a basket or boat. At the stern of the boat in this instance are shown the fine feathers D, and 20 at the bow are shown the feathers E, to give the inclosure A a unique and more symmetrical appearance.

I claim—

A design for a parlor ornament, consisting 25 of the boat-shaped inclosure A, the bird's head B, and the base C, as shown and described,

WM. H. HOYT.
